(57) **CLAIM**

The ornamental design for a vehicle lighting module, as shown and described.

DESCRIPTION

FIG. 1 is a front perspective view of a first embodiment of a vehicle lighting module showing my new design;

FIG. 2 is a front view thereof;

FIG. 3 is a top view thereof;

FIG. 4 is a bottom view thereof;

FIG. 5 is a left side view thereof;

FIG. 6 is a right side view thereof;

FIG. 7 is a front perspective view of a second embodiment of a vehicle lighting module showing my new design;

FIG. 8 is a front view thereof;

FIG. 9 is a top view thereof;

FIG. 10 is bottom view thereof;

FIG. 11 is a left side view thereof; and,

FIG. 12 is a right side view thereof.

FIGS. 7 through 12 include grayscale shading. Neither the color nor the relative brightness of the grayscale surface shading forms any part of the claimed design. The rear view is omitted and forms no part of the claimed design.

1 Claim, 12 Drawing Sheets
